(57) **CLAIM**

The ornamental design for a wave edge blind slat, as shown and described.

DESCRIPTION

FIG. 1 is an isometric view showing the new design for a wave edge blind slat;

FIG. 2 is a front view of the wave edge blind slat;

FIG. 3 is a back view of the wave edge blind slat;

FIG. 4 is a right side view of the wave edge blind slat;

FIG. 5 is a left side view of the wave edge blind slat;

FIG. 6 is a top view of the wave edge blind slat; and,

FIG. 7 is a bottom view of the wave edge blind slat.

The broken lines depict environmental structure only and form no part of the claimed design. The blind slat is shown broken away to indicate it has no specific length.
